UNITED STATES PATENT OFFICE.

CHAUNCEY F. ALLEN, OF WATERBURY, AND JAMES E. DOOLITTLE, OF BIRMINGHAM, CONNECTICUT.

CORSET-CLASP.

SPECIFICATION forming part of Letters Patent No. 244,022, dated July 12, 1881.

Application filed September 22, 1880. (Model.)

To all whom it may concern:

Be it known that we, CHAUNCEY F. ALLEN, of Waterbury, in New Haven county, State of Connecticut, and JAMES E. DOOLITTLE, of 5 Birmingham, in New Haven county, State of Connecticut, have jointly invented certain new and useful Improvements in Corset-Clasps, of which the following is a specification.

The object of this invention is a corset-busks 10 of economical construction, which may be adjusted so as to insure the fit of the corset to the body of the wearer without the employment of the ordinary eyelets and lacing.

The invention consists in providing corset- 15 busks with suitable extension devices and catches, whereby they may be adjusted and secured at different points and distances apart.

In the drawings forming part of this specification, Figure 1 is a front view of a corset 20 with busks embodying our invention; Fig. 2, a back view; and Figs. 3 and 4 represent modifications.

A represents the body of the corset-front, provided at the edges with steels or busks B 25 D. To the former are attached the fasteners, consisting of any desired number of thin metallic rigid or flexible hooks or clasps C, formed each with a series of notches or eyes, c, for the reception of the headed studs d on the busk D.

The clasps C may be secured to the steel B 30 by rivets or other connecting means; or they may be formed integral with said steel.

We show in Fig. 1 rigid hooks of thin metal; but a chain, F, Fig. 3, may be employed.

To avoid any abrasion or pinching of the 35 body of the wearer, caused by leaving a space between the two front busks, we preferably form the under steel, D, considerably wider than the steel B, so that the latter may overlap the former. 40

We claim—

A corset-busks consisting of the steels B D, one provided with a series of lugs and the other with fastening devices, each having a series of notches or eyes, c, substantially as set 45 forth.

In testimony whereof we have signed our names to this specification in the presence of two subscribing witnesses.

CHAUNCEY FREDRICK ALLEN.
JAMES E. DOOLITTLE.
